(57) **CLAIM**

The ornamental design for a terminal for mobile communication, as shown and described.

DESCRIPTION

FIG. 1 is a front perspective view of a terminal for mobile communication;

FIG. 2 is a front view of the terminal for mobile communication of FIG. 1;

FIG. 3 is a rear view of the terminal for mobile communication of FIG. 1;

FIG. 4 is a left-side view of the terminal for mobile communication of FIG. 1;

FIG. 5 is a right-side view of the terminal for mobile communication of FIG. 1;

FIG. 6 is a top plan view of the terminal for mobile communication of FIG. 1;

FIG. 7 is a bottom plan view of the terminal for mobile communication of FIG. 1; and,

FIG. 8 is an open front perspective view of the terminal for mobile communication of FIG. 1.

1 Claim, 8 Drawing Sheets
